UNITED STATES PATENT OFFICE

103,473

DESIGN FOR AN ENSEMBLE DRESS

Philip Schlessel, New York, N. Y.

Application January 23, 1937, Serial No. 67,259

Term of patent 3½ years

To all whom it may concern:

Be it known that I, Philip Schlessel, a citizen of the United States of America, residing in Manhattan, in the county of New York and State of New York, have invented a new, original, and ornamental Design for an Ensemble Dress, of which the following is a specification, reference being had to the accompanying drawing, forming part thereof, wherein,

Figure 1 is a front view of an ensemble dress showing my new design.

Figure 2 is a rear view of the ensemble dress shown in Figure 1.

The characteristic feature of the design resides in the combination on the ensemble as shown of the split epaulets on the shoulders of the jacket member, said epaulets being a continuation of the sleeves and rise out of the deep central sleeve fold as shown.

I claim:

The ornamental design for an ensemble dress, substantially as shown and described.

PHILIP SCHLESSEL.
